UNITED STATES PATENT OFFICE.

BENJAMIN F. HECHT, OF BALTIMORE, MARYLAND.

DESIGN FOR A BUCKLE.

SPECIFICATION forming part of Design No. 35,441, dated December 17, 1901.

Application filed October 24, 1901. Serial No. 79,883. Term of patent 14 years.

To all whom it may concern:

Be it known that I, BENJAMIN F. HECHT, a citizen of the United States, residing at Baltimore, in the State of Maryland, have invented and produced a new and original Design for a Buckle, of which the following is a specification.

Reference is to be had to the accompanying drawings, in which—

10 Figure 1 is a front view of the buckle, and Fig. 2 is an end view thereof.

The frame of the buckle is of substantially rectangular shape, being a rod of metal, forming four sides. Between two opposite sides 15 of said rectangular frame appear two transverse bars, parallel with respect to each other, and said two frame sides and said bars are of

greater size in both diameter and length than the frame sides with which they are parallel, as shown in the drawings. Both ends of each 20 transverse bar appear projecting beyond the two frame sides with which they are at right angles, as plainly illustrated in the drawings.

Having thus described my invention, what I claim is—

25 The design for a buckle herein shown and described.

In testimony whereof I affix my signature in the presence of two witnesses.

BENJAMIN F. HECHT.

Witnesses:

THOS. C. BAILEY,
CHARLES L. VIETSCH.
